COMBINED STEAM AND COMBUSTION GAS POWER PLANT

Application filed October 2, 1926. Serial No. 139,173.

My present invention relates to power plants utilizing both steam and explosion gases as the driving medium, and has for its object to derive the heat required for the generation of steam, solely from the explosion gases serving as a power medium, so as to avoid the use of any separate steam boiler furnace. In the preferred form of my invention, power is developed in three stages, 10 the high pressure stage using jets of explosion gases as a driving medium, the latter also serving to heat the steam which is on its way to the intermediate pressure stage; this steam may also exert a driving action in the 15 high pressure stage, or it may pass therethrough simply to absorb heat from the blades and other turbine parts exposed to the combustion gases. In the intermediate stage, both the explosion gases and the steam (both 20 coming from the high pressure stage) exert a driving action, and the steam again absorbs heat from the combustion gases by way of the turbine blades. It will thus be seen that in the high pressure stage and in the intermediate 25 stage, the steam will exert a cooling action on the engine parts heated by the combustion gases. In the low pressure stage, I generally employ a single driving fluid, which is the steam exhausting from the 30 intermediate pressure stage. The heat of the combustion gases exhausting from one of the gas turbine stages is utilized to generate steam for the high pressure stage.

An arrangement suitable for carrying out 35 my present invention is illustrated by the accompanying drawings, in which Fig. 1 is a somewhat diagrammatic general view, with parts in section, and Fig. 2 a view through the intermediate turbine between a 40 steam nozzle and its associated catch nozzle.

Air and fuel are supplied under pressure at regular intervals to one or more explosion chambers 10 which, as shown in Fig. 1 of the drawings, are provided with inlet valves 45 at the right thereof for intermittently charging therewith mixtures of such air and fuel, as disclosed more fully in my United States Patent No. 877,194. After ignition has been effected in any suitable manner, the explosion 50 gases are allowed (upon the opening of ap-

propriate valves 11) to pass to combustion gas nozzles discharging jets against the blades 12 of a high pressure rotor 13. Against these blades is also discharged steam issuing from nozzles 14, and after passing through the rotor 13, this steam is collected by catch nozzles 15. The pressure of this steam may be sufficient to exert an auxiliary driving action on the high pressure rotor 13, or the steam may have for its sole function (so far as the high pressure stage is concerned) to absorb heat from this stage and cool it, particularly the rotor blades 12. In any event, however, the steam thus heated in the high pressure stage has a sufficient pressure to exert a driving action on the intermediate pressure turbine, to the steam nozzles 16 of which it passes from the catch nozzles 15 through a suitable conduit 17. The rotor 18 of the intermediate stage is driven by the steam issuing from the nozzles 16 and also by the exhaust combustion gases issuing from nozzles 19 to which they are conveyed by a conduit 20 from the exhaust chamber 21 of the high pressure stage. From the intermediate 75 pressure stage, the steam, collected by catch nozzles 22, passes through a pipe 23 to a low pressure steam turbine 24 and then to a condenser 25. The combustion gases exhausting from the intermediate pressure turbine pass through a pipe 26 to a casing 27 and then out to the atmosphere. In the casing 27 is arranged a boiler or container 28 for water from which steam is generated by the heat of the exhaust gases, such steam being then conveyed by a conduit 29 to the nozzles 14 of the high pressure stage.

It will be clear from the above that no separate furnace or source of heat is required for the generation of steam for cooling purposes, as I have found that the heat of the exhaust explosion gases suffices for this purpose.

Various changes in the specific forms shown and described may be made within the scope of the claims without departing from the 95 spirit of my invention.

I claim:

1. A power plant comprising a plurality of explosion chambers adapted to be intermittently charged with an explosive mixture for 100

explosion therein, a high pressure turbine having nozzles for high pressure steam and high pressure combustion gases respectively, said gas nozzles being connected to said explosion chambers to receive therefrom intermittent jets of explosion gases, means for collecting separately the steam and the explosion gases exhausting from said explosion turbine, said gases exhausting at a pressure above atmospheric, a second turbine likewise having steam nozzles and combustion gas nozzles, such nozzles receiving their supply from the exhaust of the high pressure turbine, the gases exhausting from said second turbine at substantially atmospheric pressure, a steam boiler arranged in the path of the gases exhausting from one of said turbines and heated exclusively by said gases, there being no additional source of heat devoted to the generation of steam, and conduits for conveying the steam produced in said boiler to the steam nozzles of said high pressure turbine, the gases exhausting from the second turbine being ultimately discharged into the atmosphere without being caused to perform additional mechanical work.

2. A power plant as set forth in claim 1 including a low pressure steam turbine receiving its motive steam from the exhaust of the second-mentioned turbine.

3. A power plant comprising a high pressure turbine with nozzles for high pressure steam and high pressure combustion gases respectively and means for collecting separately the exhaust steam and the exhaust combustion gases, an intermediate multi-stage turbine likewise having steam nozzles and combustion gas nozzles, such nozzles receiving their supply from the exhaust of the high pressure turbine, a low pressure condensing steam turbine receiving its motive steam from the exhaust of said intermediate multi-stage turbine, a steam boiler connected to the gas exhaust of said intermediate turbine and heated by the exhaust combustion gases from said intermediate turbine and having an outlet for said exhaust gases opening into the atmosphere, and means for conducting the steam generated in such boiler to the steam nozzles of the high pressure turbine.

4. A power plant comprising an explosion chamber, a valve controlling the outlet of said chamber, a high pressure turbine having a nozzle for high pressure steam, another nozzle connected with said outlet to receive high pressure combustion gases from said explosion chamber whenever said valve is open, and a rotor in operative relation to said nozzles; a collector to receive the successive jets of combustion gases issuing from said rotor, an intermediate pressure multi-stage turbine having a steam nozzle and a combustion gas nozzle, a connection from said collector to the combustion gas nozzle of said intermediate turbine, another connection to convey exhaust

steam from said high pressure turbine to the steam nozzle of the intermediate pressure turbine, the latter having separate outlets for exhaust steam and exhaust combustion gases respectively, a low pressure condensing turbine receiving its motive steam from the steam outlet of said intermediate pressure multi-stage turbine, a steam boiler heated by the exhaust combustion gases from said intermediate pressure turbine, and having an outlet to discharge the said gases into the atmosphere, and a conduit for conveying the steam generated in such boiler to the steam nozzle of the high pressure turbine.

In testimony whereof I have hereunto set my hand.

HANS HOLZWARTH.
